(57) **CLAIM**

The ornamental design for a rack for dishwasher basket, as shown and described.

DESCRIPTION

FIG. 1 is a top front perspective view of a rack for dishwasher basket showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof; and,

FIG. 7 is a bottom rear perspective view.

The dashed broken lines in the figures show portions of the rack for dishwasher basket that form no part of the claimed design.

1 Claim, 7 Drawing Sheets
